Dec. 13, 1960

W. BERG

2,963,817

UNITARY FOLDABLE MUSIC STAND

Filed Feb. 5, 1959

FIG. 1

FIG. 2

FIG. 3

FIG. 4

INVENTOR.
WILLIE BERG

BY

Bianman & Bianman
ATTORNEYS

6. A foldable stand according to claim 5 characterized in that the apex of said third leg when folded is in substantial contact with the apices of said two legs at a point beyond the adjacent edge of said table.

7. A foldable stand according to claim 1 characterized in that the hinged ends of said legs are provided with stops at an angle to said legs and adapted to lie against said under side when said legs are unfolded.

References Cited in the file of this patent

UNITED STATES PATENTS

2,383,287 Berg Aug. 21, 1945
2,808,304 Smith Oct. 1, 1957

FOREIGN PATENTS

1,108,866 France Jan. 18, 1956